UNITED STATES PATENT OFFICE.

NATHANIEL BALDWIN, OF MILL CREEK, UTAH.

SOUND-PRODUCING DEVICE OF THE TELEPHONE-RECEIVER TYPE.

Application filed June 14, 1922. Serial No. 568,163.

To all whom it may concern:

Be it known that I, NATHANIEL BALDWIN, a citizen of the United States, residing at Mill Creek, in the county of Salt Lake and State of Utah, have invented new and useful Improvements in Sound-Producing Devices of the Telephone-Receiver Type, of which the following is a description, reference being had to the accompanying drawings and to the letters and figures of reference marked thereon.

The invention relates to new and useful improvements in telephone-receivers, and more particularly to certain improvements in my prior Patent No. 1,153,593, issued September 14, 1915.

One object of the invention is to secure a more sensitive sound producing instrument by the employment of a relatively smaller diaphragm. Another object is to secure an extended air chamber between the diaphragm and the supporting base frame. Another object is to secure convenience of construction while assembling the parts of the receiver.

These and other objects are attained by employing a seat collar, which is supported on its outer flange by the base frame and which supports the diaphragm upon its inner flange.

The accompanying drawings more fully explain this invention.

Figure 1 is a top plan of the seat collar. Figure 2 is a cross section of the seat collar. Figure 3 is a metrical section of a watch case form showing the seat collar in position. Figure 4 is a vertical view of a funnel-shaped receiver, partly torn away, showing the seat collar in position.

In the Figures 3 and 4 the seat collar 1 resting by its outer flange upon the shoulder of the base frame or cup 2 and the seat collar 1 is supporting upon its inner flange the diaphragm 3. Cup 2 is in turn seated on the rim of the enclosing casing. The chamber between the diaphragm 3 and the base

frame 2 is extended outwardly, under the seat collar. While assembling the parts, during the construction of the receiver, the binding post 4 may be easily reached before the diaphragm 3 is fastened down which is an advantage.

What I claim as new and desire to secure Letters Patent on is as follows:

1. A telephone receiver having an enclosing casing containing an electromagnet, a seating collar mounted in said casing in position relative to the said magnet and provided with a circular depressed ledge formed in a central offset portion of said collar and concentrically surrounding a central aperture therein, and a diaphragm seated on said ledge and covering the aperture.

2. A telephone receiver having a casing containing an electromagnet, a movable armature for said electromagnet, means biasing said armature toward one end position, a seating collar mounted in said casing in position relative to the said magnet and armature and provided with an aperture having an inwardly projecting ledge, a diaphragm seated in said aperture and on said ledge, and means to connect said armature and said diaphragm, said means serving to transmit movements therebetween and to retain said diaphragm in said aperture.

3. In a telephone receiver, an enclosing casing having an internal seat, a diaphragm of diameter substantially less than the diameter of the casing, a seating collar having a peripheral edge to be received in said seat and a central thicker portion to hold said collar centered with regard to said casing, and a circular offset ledge surrounding a central aperture and adapted to receive and hold the diaphragm with one of its surfaces substantially flush with the inward surface of the collar, whereby an air pocket is provided at the outer face of said diaphragm.

NATHANIEL BALDWIN.
